UNITED STATES PATENT OFFICE.

MICHAEL COMFORT, OF PLANTSVILLE, CONNECTICUT, ASSIGNOR OF ONE-FOURTH TO
MARY TRYBULSKI, OF MILLDALE, CONNECTICUT, AND ONE-FOURTH TO
WOJCIECH ALIAS GEORGE TRYBULSKI, OF MILLDALE, CONNECTICUT.

GLOBE CLOCK.

Application filed March 13, 1924. Serial No. 698,933.

To all whom it may concern:

Be it known that I, MICHAEL COMFORT, a citizen of the United States of America, residing at Plantsville, in the county of Hartford and State of Connecticut, have invented certain new and useful Improvements in Globe Clocks, of which the following is a specification.

This invention relates to certain new and useful improvements in clocks and has for its primary object to provide a clock wherein the clock casing is of spherical formation and is supported at the equator or transverse median line thereof.

Another object of the invention is to provide a clock of spherical formation wherein a central transverse disk plate rotatably supports adjacent edges of hemispherical casing sections with the casing sections reversely 20 rotatable through the medium of clock mechanism, one section indicating time in minutes while the other section indicates time in hours.

With the above and other objects in view and others that will appear as the nature of the invention is better understood, the same consists of the novel form, combination and arrangement of parts hereinafter more fully described, shown in the accompanying drawings and claimed.

In the accompanying drawings, wherein like reference characters designate corresponding parts throughout the several views,

Figure 1 is a side elevation view of a spherical clock constructed in accordance with the present invention, the suspension chains therefor being partially broken away.

Figure 2 is a top plan view of the clock showing the winding key for the clock mechanism by dotted lines,

Figure 3 is a vertical cross-sectional view taken on line III—III of Fig. 2 showing the gears of the clock train meshing with circular rack teeth on the upper and lower hemispherical sections of the clock casing,

Figure 4 is a detail sectional view taken on line IV—IV of Fig. 3,

Figure 5 is a horizontal sectional view taken on line V—V of Fig. 1 showing the clips for retaining one of the hemispherical

sections rotatably supported upon the central disk plate and the clock mechanism within the clock casing,

Figure 6 is a detail sectional view taken on line VI—VI of Fig. 1 showing the winding stem for the clock mechanism, and

Figure 7 is a side elevational view, partly in section of the clock key.

Briefly described, the present invention aims to provide a clock wherein the clock casing is of spherical formation embodying upper and lower hemispherical casing sections that are rotatably supported at their meeting edges upon a central disk plate. Clock mechanism supported upon the disk plate within the connected casing sections has certain gears of the clock train mechanism meshing with circular rack teeth upon the inner faces of the casing section, the gear ratio causing the upper hemispherical section of the clock casing carrying minute indicia to travel in a complete revolution while the lower casing section providing the hour indicia travels one-twelfth of a circle. The central disk plate has an exposed annular flange that carries indicator points directed toward the minute and hour indicia so that accurate time may be read at the transverse median line of the clock casing.

Referring more in detail to the accompanying drawings there is illustrated a spherical clock casing embodying a central disk plate 1 with which the meeting edges of upper and lower hemispherical clock casing sections 2 and 3, respectively, are associated.

The disk plate 1 is outwardly arched at its peripheral edge as at 4 and carries upwardly and downwardly extending flanged edges 5 and 6 while the meeting edges of the upper and lower casing sections 2 and 3 are angularly directed inwardly as at 7 to extend parallel with the adjacent faces of the disk plate 1 as clearly shown in Fig. 3. The connecting means between the disk plate 1 and the casing sections 2 and 3 includes angle clips 8 secured as at 9 to the disk plate with their outer ends freely enclosing the angle edges 7 of the casing sections, bearing balls 10 being interposed between the casing flange 7 of the casing section 2 and the disk plate 1 and between the flange 7 of the lower

casing section 3 and the associated angle clips 8, as shown in Fig. 3, for the purpose of reducing friction and permitting free rotation of the casing sections. Access to the 5 interior of the connected casing sections 2 and 3 is facilitated by the provision of hand entrance openings at the vertical axis of the casing sections 2 and 3 that are closed by threaded arched disks 11 of a curvature 10 incident to the curvature of said casing sections and as clearly shown in Figs. 1 and 3. The suspension means for the clock casing includes the provision of outwardly directed arms 12 and 13 to which suspension chains 14 are attached for suspending the clock casing in any convenient manner.

The clock mechanism is disposed within the casing sections and supported upon the disk plate 1 adjacent the bracket arm 13 and embodies a base plate 15 directly mounted upon the upper face of the disk plate 1 and spaced from the upper plate 16 by the post 17, this construction being clearly shown in Fig. 3. The main shaft 18 of the 20 clock mechanism has the main spring 19 associated therewith while a bevel pinion 20 fixed to the lower end of the shaft 18 extends into the cutaway portion 21 formed in the disk plate 1. A winding stem 22 is 25 journaled in the opening 23 formed in the disk plate that communicates with the cutaway portion 21 and a beveled pinion 24 secured to the inner end of the winding stem 23 within the cutaway portion 21 30 meshes with the bevel pinion 20 upon the lower end of the shaft 18. The bracket arm 13 is of tubular formation as shown in Fig. 6 and the winding stem 23 extends thereinto 35 to be engaged by the wrench end 25 of the winding key 26 shown in Fig. 7. The clock mechanism further includes a bearing 27 supported upon the lower face of the disk plate 1 and depending therefrom having a shaft journaled therein that is in gear communication with the shaft 18, a pinion 28 40 associated with the shaft in the bearing 27 meshing with a relatively large gear 29 secured to a shaft journaled in the bearing 30 depending from the disk plate with the gear 29 meshing with a circular series of rack teeth 31 formed upon the inner face 45 of the casing section 3 adjacent the disk plate 1 as clearly shown in Fig. 3, the speed of rotation of the casing section 3 being reduced by the gear ratio as described. A shaft 32 journaled in the plates 15 and 16 50 has gear connections with the shaft 18 and has a relatively large gear 33 secured thereto that is in mesh with the pinion 34 fixed 55 to a shaft journaled in a bearing 35 depending from the upper plate 16, the pinion 34 meshing with a circular series of rack teeth 36 formed upon the inner face of the casing section 2 adjacent the upper side of the 60 disk plate 1. From the above description 65

of the clock mechanism, it will be understood that the lower casing section 3 revolves in a clockwise movement while the upper casing section 2 revolves in a counter-clockwise movement, and by the gear ratio, the 70 upper casing section is caused to travel in one complete revolution while the lower casing section revolves one-twelfth of a revolution. Alarm devices 37 are associated with the clock mechanism and may be of a 75 conventional type for striking hours and half hours.

The outer face of the casing section 2 adjacent the peripheral edge 4 of the disk plate is provided with a circular series of 80 minute graduations 38 having minute numerals 39 associated therewith while the casing section 3 has hour graduations 40 arranged in a similar manner and with which hour numerals 41 are associated. 85 The peripheral edge 4 of the disk plate 1 carries indicator points 42 and 43 associated with the minute and hour graduations as shown in Figs. 1 and 3 so that accurate time 90 may be obtained.

From the above detail description of the clock and its associated mechanism, it is thought that the construction and operation thereof should at once be understood, it being noted that the gearing train of 95 the clock mechanism causes the upper and lower casing sections 2 and 3 to revolve in opposite directions, the gear ratio for the upper section causing the same to travel in one complete revolution indicating minutes while the gear ratio for the lower casing section causes the latter to revolve one-twelfth of a revolution during the same period of time for indicating one hour. The 100 minute and hour graduations 38 and 40 upon the outer faces of the casing sections when viewed in connection with the indicator points 42 and 43 will give the accurate time and a clock of extremely novel appearance and practicability is herein provided. The winding of the clock mechanism is accomplished by inserting the key 105 26 in the tubular bracket arm 13 for engaging the winding stem 23 and the alarm mechanism may be associated with the main 110 spring 19 for simultaneously winding the 115 same.

While there is herein shown and described the preferred embodiment of the present invention it is nevertheless to be understood that minor changes may be made therein without departing from the spirit and scope of the invention as claimed.

What is claimed as new is:—

1. In a clock of the type described, a 125 spherical casing formed of hemispherical sections, a disk plate interposed between the two sections, minute and hour indicia upon the respective sections, clock mechanism within the casing for reversely rotating the 130

- casing sections, and indicator pointers carried by the peripheral edge of the disk plate associated with the time indicia.
2. In a clock of the type described, a spherical casing formed of hemispherical sections, a disk plate interposed between the two sections, minute and hour indicia upon the respective sections, clock mechanism within the casing for reversely rotating the casing sections, indicator pointers carried by the peripheral edge of the disk plate associated with the time indicia, the peripheral edge of the disk plate extending outwardly of the casing sections, radial arms carried by the edge of the plate, and suspension means for the clock casing secured to said arms. 70
3. In a clock of the type described, a spherical casing formed of hemispherical sections, a disk plate interposed between the two sections, minute and hour indicia upon the respective sections, clock mechanism within the casing for reversely rotating the casing sections, indicator pointers carried by the peripheral edge of the disk plate associated with the time indicia, the peripheral edge of the disk plate extending outwardly of the casing sections, radial arms carried by the edge of the plate, suspension means for the clock casing secured to said arms, the clock mechanism being supported on the plate adjacent one of the arms, and said last named arm being constructed to permit winding of the clock mechanism. 80
4. In a clock of the type described, a spherical casing formed of hemispherical sections, a disk plate interposed between the two sections, minute and hour indicia upon the respective sections, clock mechanism within the casing for reversely rotating the casing sections, and indicator pointers carried by the peripheral edge of the disk plate associated with the time indicia, said clock mechanism including a gear train and circular series of rack teeth on the inner faces of the casing sections engaged by gears of the train with the gear of a ratio to cause the casing section bearing the minute indicia to make one complete revolution while the casing section bearing the hour indicia travels one-twelfth of a revolution. 90
5. In a clock of the type described, a spherical casing formed of hemispherical sections, a disk plate interposed between the two sections, minute and hour indicia upon the respective sections, clock mechanism within the casing for reversely rotating the casing sections, indicator pointers carried by the peripheral edge of the disk plate associated with the time indicia, the peripheral edge of the disk plate extending outwardly of the casing sections, radial arms carried by the edge of the plate, and suspension means for the clock casing secured to said arms, said clock mechanism including a gear train and circular series of rack teeth on the inner faces of the casing sections arranged parallel with the disk plate, angle clips secured to the disk plate and overlying the adjacent edges of the flanges, and anti-friction bearings interposed between the casing flanges and disk plate. 100
6. In a clock of the type described, a spherical casing formed of hemispherical sections, a disk plate interposed between the two sections, minute and hour indicia upon the respective sections, clock mechanism within the casing for reversely rotating the casing sections, indicator pointers carried by the peripheral edge of the disk plate associated with the time indicia, the peripheral edge of the disk plate extending outwardly of the casing sections, radial arms carried by the edge of the plate, suspension means for the clock casing secured to said arms, the connection between the hemispherical sections and disk plate including inwardly directed flanges at the free edges of the casing sections arranged parallel with the disk plate, angle clips secured to the disk plate and overlying the adjacent edges of the flanges, and anti-friction bearings interposed between the casing flanges and disk plate. 110
7. In a clock of the type described, a spherical casing formed of hemispherical sections, a disk plate interposed between the two sections, minute and hour indicia upon the respective sections, clock mechanism within the casing for reversely rotating the casing sections, indicator pointers carried by the peripheral edge of the disk plate associated with the time indicia, the peripheral edge of the disk plate extending outwardly of the casing sections, radial arms carried by the edge of the plate, suspension means for the clock casing secured to said arms, the connection between the hemispherical sections and disk plate including inwardly directed flanges at the free edges of the casing sections arranged parallel with the disk plate, angle clips secured to the disk plate and overlying the adjacent edges of the flanges, and anti-friction bearings interposed between the casing flanges and disk plate. 120
8. In a clock of the type described, a spherical casing formed of hemispherical sections, a disk plate interposed between the two sections, minute and hour indicia upon the respective sections, clock mechanism within the casing for reversely rotating the casing sections, indicator pointers carried by the peripheral edge of the disk plate associated with the time indicia, the peripheral edge of the disk plate extending outwardly of the casing sections, radial arms carried by the edge of the plate, suspension means for the clock casing secured to said arms, the connection between the hemispherical sections and disk plate including inwardly directed flanges at the free edges of the casing sections arranged parallel with the disk plate, angle clips secured to the disk plate and overlying the adjacent edges of the flanges, and anti-friction bearings interposed between the casing flanges and disk plate. 130

parallel with the disk plate, angle clips secured to the disk plate and overlying the adjacent edges of the flanges, and anti-friction bearings interposed between the casting flanges and disk plate.

9. In a clock of the type described, a spherical casing formed of hemispherical sections, a disk plate interposed between the two sections, minute and hour indicia upon the respective sections, clock mechanism within the casing for reversely rotating the casing sections, indicator pointers carried by the peripheral edge of the disk plate associated with the time indicia, the peripheral edge of the disk plate extending outwardly of the casing sections, radial arms carried by the edge of the plate, suspension means for the clock casing secured to said arms, the clock mechanism being supported on the plate adjacent one of the arms, said last named arm being constructed to permit winding of the clock mechanism, the connection between the hemispherical sections and disk plate including inwardly directed flanges at the free edges of the casing sections arranged parallel with the disk plate, angle clips secured to the disk plate and overlying the adjacent edges of the flanges, and anti-friction bearings interposed between the casing flanges and disk plate.

10. In a clock of the type described, a spherical casing formed of hemispherical sections, a disk plate interposed between the two sections, minute and hour indicia upon the respective sections, clock mechanism within the casing for reversely rotating the casing sections, indicator pointers carried by the peripheral edge of the disk plate, associated with the time indicia, said clock mechanism including a gear train and circular series of rack teeth on the inner faces of the casing sections engaged by gears of the train with the gear of a ratio to cause the casing section bearing the minute indicia to make one complete revolution while the casing section bearing the hour indicia travels one-twelfth of a revolution, the connection between the hemispherical sections and disk plate including inwardly directed flanges at the free edges of the casing sections arranged parallel with the disk plate, angle clips secured to the disk plate and overlying the adjacent edges of the flanges and anti-friction bearings interposed between the casing flanges and disk plate.

11. In a clock of the type described, a spherical casing formed of hemispherical sections, a disk plate interposed between the two sections, minute and hour indicia upon the respective sections, clock mechanism within the casing for reversely rotating the casing sections, indicator pointers carried by the peripheral edge of the disk plate associated with the time indicia, the periph-

12. In a clock of the type described, a spherical casing formed of hemispherical sections, a disk plate interposed between the two sections, minute and hour indicia upon the respective sections, clock mechanism within the casing for reversely rotating the casing sections, indicator pointers carried by the peripheral edge of the disk plate associated with the time indicia, the peripheral edge of the disk plate extending outwardly of the casing sections, radial arms carried by the edge of the plate, suspension means for the clock casing secured to said arms, the clock mechanism being supported on the plate adjacent one of the arms, said last named arm being constructed to permit winding of the clock mechanism, said clock mechanism including a gear train and circular series of rack teeth on the inner faces of the casing sections engaged by gears of the train with the gear of a ratio to cause the casing section bearing the minute indicia to make one complete revolution while the casing section bearing the hour indicia travels one-twelfth of a revolution, the connection between the hemispherical sections and disk plate including inwardly directed flanges at the free edges of the casing sections arranged parallel with the disk plate, angle clips secured to the disk plate and overlying the adjacent edges of the flanges, and anti-friction bearings interposed between the casing flanges and disk plate.

13. In a clock of the type described, a spherical casing formed of hemispherical sections, a disk plate interposed between the two sections, minute and hour indicia upon the respective sections, clock mechanism within the casing for reversely rotating the casing sections, indicator pointers carried by the peripheral edge of the disk plate associated with the time indicia, said clock mechanism including a gear train and circular series of rack teeth on the inner 120

faces of the casing sections engaged by the gears of the train, a relatively small pinion of the train engaging the rack teeth on the casing section bearing the minute indicia 5 and a relatively large gear engaging the rack teeth on the hour indicia bearing casing section to cause the casing section bearing the minute indicia to move in a complete revolution while the hour indicia bearing 10 casing section moves through one-twelfth of a revolution.

14. In a clock of the type described, a spherical casing formed of hemispherical sections, a disk plate interposed between the 15 two sections, minute and hour indicia upon the respective sections, clock mechanism within the casing for reversely rotating the casing sections, indicator pointers carried by the peripheral edge of the disk plate associated with the time indicia, the peripheral edge of the disk plate extending outwardly of the casing sections, radial arms carried by the edge of the plate, suspension 20 means for the clock casing secured to said arms, the clock mechanism being supported on the plate adjacent one of the arms, said last named arm being constructed to permit winding of the clock mechanism, said clock mechanism including a gear train 25 and circular series of rack teeth on the inner faces of the casing sections engaged by the gears of the train, a relatively small pinion of the train engaging the rack teeth on the casing section bearing the minute indicia 30 and a relatively large gear engaging the rack teeth on the hour indicia bearing casing section to cause the casing section bearing the minute indicia to move in a complete revolution while the hour indicia bearing 35 casing section moves through one-twelfth of a revolution.

15. In a clock of the type described, a spherical casing formed of hemispherical sections, a disk plate interposed between the two sections, minute and hour indicia upon the respective sections, clock mechanism within the casing for reversely rotating the casing sections, indicator pointers carried by the peripheral edge of the disk plate associated with the time indicia, the peripheral edge of the disk plate extending outwardly of the casing sections, radial arms carried by the edge of the plate, suspension means for the clock casing secured to said arms, the clock mechanism being supported on the plate adjacent one of the arms, said last named arm being constructed to permit winding of the clock mechanism, said clock mechanism including a gear train and circular series of rack teeth on the inner faces of the casing sections engaged by the gears of the train, a relatively small pinion of the train engaging the rack teeth on the casing section bearing the minute indicia 60 and a relatively large gear engaging the rack teeth on the hour indicia bearing casing section to cause the casing section bearing the minute indicia to move in a complete revolution while the hour indicia bearing casing section moves through one-twelfth of a revolution.

In testimony whereof I affix my signature.

MICHAEL COMFORT.
